UNITED STATES PATENT OFFICE.

BENJAMIN F. MAYO, OF SALEM, MASSACHUSETTS, ASSIGNOR TO UNITED SHOE MACHINERY COMPANY, OF PATERSON, NEW JERSEY, A CORPORATION OF NEW JERSEY.

CHANNELING AND GROOVING KNIFE.

No. 911,512.

Specification of Letters Patent.

Patented Feb. 2, 1909.

Application filed April 4, 1905, Serial No. 253,782. Renewed June 20, 1908. Serial No. 439,596.

To all whom it may concern:

Be it known that I, BENJAMIN F. MAYO, a citizen of the United States, residing at Salem, in the county of Essex and State of Massachusetts, have invented certain new and useful Improvements in Channeling and Grooving Knives; and I do hereby declare the following to be a full, clear, and exact description of the invention, such as will enable others skilled in the art to which it appertains to make and use the same.

The present invention relates to an improved channeling and grooving knife and has for its object to provide a knife by which a channel can be readily cut in a shoe sole and simultaneously a strip of material removed from the sole to form a fastening receiving groove in the channel extending the length of the channel at a uniform distance from the base of the channel flap or lip.

Heretofore when the operations of cutting a channel and removing a strip of material to form a groove in the channel have been performed simultaneously two separate knives have usually been employed. The use of separate knives, however, necessitates placing the grooving knife back of the channeling knife and as a consequence the cutting edge of the grooving knife is displaced whenever the sole or the knife holder is turned in cutting around a curve or angle of the sole. This displacement of the cutting edge of the grooving knife increases with the sharpness of the curve or angle and prohibits the simultaneous use of the knives on certain styles of soles as, for instance, soles with narrow or pointed toes or soles which present sharp curves or angles at the junction of the shank and forepart.

In accordance with the present invention the cutting edges which cut the channel and remove a strip of material to form a groove in the channel are formed on the same knife and are arranged in a plane substantially perpendicular to the direction in which the knife cuts. This arrangement of the cutting edges allows the sole or the knife holder to be turned through any desired angle without displacing the groove cutting edge and consequently the knife can be used to channel and groove all styles of soles. Preferably the channel cutting or lip forming edge extends at its inner end beyond the groove forming edge as in such case the

inner end of the knife blade can be made thin to allow the knife to cut through the stock without being cramped. The portion of the knife which terminates in the groove cutting edge and which acts as a groove cutting blade preferably projects obliquely from the surface of that portion of the knife which acts as a channel cutting or lip forming blade in order to prevent any binding or cramping action of the groove cutting blade in the groove during the turning movements of the sole or of the knife holder.

The features of the present invention will be clearly understood from an inspection of the drawing accompanying this application, in which—

Figure 1 is a perspective view on an enlarged scale of the improved channeling and grooving knife and also showing a portion of a shoe sole which has been acted upon by the knife, Fig. 2 is a plan view of the knife, Fig. 3 a view in front elevation of the knife, Fig. 4 is an end view of the knife, Fig. 5 is a sectional view taken on the line 5—5 of Fig. 3, Fig. 6 is a view illustrating the action upon a shoe sole of separate channeling and grooving knives when used in a sole rounding and channeling machine comprising a relatively movable pattern and knife carrier, and Fig. 7 is a view illustrating the action upon a shoe sole of my improved channeling and grooving knife when used in the same kind of a machine.

The knife illustrated in the drawing as embodying the present invention comprises a shank portion 1 adapted to be clamped in a suitable holder and a blade portion 2 offset with relation to the shank and connected thereto by a curved portion 3. Upon the blade portion 2 are formed two cutting edges 4 and 5, the edge 4 being adapted to cut a channel in the sole and form a channel flap or lip and the edge 5 being adapted to remove a strip of material from the sole to form a fastening receiving groove in the channel. The edge 4 is continuous from its outer end 6 to its inner end 7 and curves sharply at the point 8 in order to form a shoulder at the outer end of the channel and cut a lip having a comparatively thick edge. The groove cutting edge 5 merges into the channel cutting edge 4 and is arranged in substantially the same plane with the edge 110

4 perpendicular to the direction in which the knife cuts. At its inner end the edge 4 extends beyond the groove cutting edge 5 and the inner end of the knife blade back of 5 the cutting edge 4 is reduced in thickness, so that a comparatively thin edge is formed at the inner end of the blade. The blade portion of the knife is provided with a passage 10 way for the strip of material removed by the cutting edge 5, which extends from the cutting edges at the mouth of the passage way obliquely with relation to the direction in which the knife cuts and with relation to the cutting edge 4 in order that the strip of 15 material may be properly directed away from the work. The portion of the knife upon which the cutting edge 5 is formed and which acts as a groove cutting blade projects obliquely from the surface of that portion of 20 the knife which acts as a channel cutting and lip forming blade, as is clearly illustrated in Figs. 4 and 5. This arrangement of the groove cutting blade prevents the blade from becoming cramped in the groove 25 while cutting around sharp curves or angles in the sole.

The manner in which the channeling and grooving knife above described acts upon a shoe sole is clearly illustrated in Figs. 1 and 30 7. As the knife passes through the material of the sole the cutting edge 4 forms a lip 9 and the cutting edge 5 removes a strip of material from the sole to form the fastening 35 receiving groove 10. Since the cutting edge 4 at its inner end extends beyond the cutting edge 5 the groove 10 is formed at a distance from the base of the lip 9 sufficient to allow the lip to be displaced by the knife blade without exerting an objectionable cramping 40 pressure thereon. At its base the lip cannot be displaced readily to any appreciable extent and for this reason the inner end of the knife is reduced to a thin edge. As the sole or knife is swung in cutting around 45 sharp curves or angles of the sole the cutting edge 5 remains at the same distance from the base of the channel flap or lip formed by the cutting edge 4 and consequently the groove formed in the channel extends the length of 50 the channel at a uniform distance from the base of the lip, this result being due to the fact that the cutting edge 5 is in substantially the same plane with the cutting edge 4 perpendicular to the direction in which the 55 knife cuts. This result cannot be secured by the use of separate channeling and grooving knives as in such case the grooving knife is necessarily placed at the rear of the channeling knife and is moved outwardly away from

the base of the channel flap when the sole or 60 the holder in which the knives are secured is swung in cutting around sharp curves or angles of the pattern. In Fig. 6 the effect of this displacement of the grooving knife is indicated at 11, the groove 10 bending 65 abruptly outward as it passes around the toe portion of the sole. By the use of a channeling and grooving knife constructed in accordance with the present invention a sole 70 of the shape illustrated in Fig. 6 can be simultaneously channeled and grooved and the groove maintained at a uniform distance from the base of the channel flap, as indicated in Fig. 7.

The nature and scope of the present invention having been indicated and a knife embodying the same having been specifically described, what is claimed is:—

1. A channeling and grooving knife having a continuous lip forming cutting edge, 80 and a groove forming cutting edge located in substantially the same plane with the lip forming cutting edge perpendicular to the direction in which the knife cuts, substantially as described.

2. A channeling and grooving knife having a continuous lip forming cutting edge, and a groove forming cutting edge located in substantially the same plane with the lip forming cutting edge perpendicular to the 90 direction in which the knife cuts, said lip forming cutting edge at its inner end extending beyond the groove forming cutting edge, substantially as described.

3. A channeling and grooving knife having a lip forming blade provided with a continuous cutting edge, and a groove forming blade extending obliquely from the surface of the lip forming blade and provided with a cutting edge in substantially the same 100 plane with the cutting edge of the lip forming blade perpendicular to the direction in which the knife cuts, substantially as described.

4. A channeling and grooving knife having a lip forming blade provided with a continuous cutting edge, and a groove forming blade integral with and extending from the lip forming blade, the cutting edge of the lip forming blade at its inner end extending beyond the cutting edge of the groove forming blade, substantially as described.

In testimony whereof I affix my signature, in presence of two witnesses.

BENJAMIN F. MAYO.
